C. DIETRICH'S

GAME BOARD

Filed July 21, 1926

Patented Oct. 4, 1927.

1,644,514

UNITED STATES PATENT OFFICE.

CHARLES DIETRICH, OF LITTLE FERRY, NEW JERSEY.

GAME BOARD.

Application filed July 21, 1926. Serial No. 123,881.

This invention relates to game apparatus of the kind in which a ball or marble is projected against the surface of a game board at a target of some kind, such as a group of 5 pockets of different valuations or a group of ten-pins, or the like.

The invention of this application has to do with the means for projecting the ball or marble, and is not concerned with the 10 particular form of target at which the ball is directed.

The object of the invention is to provide a projecting device for games of this character wherein chance and skill are combined in 15 a manner to render the game interesting without requiring any great degree of practice to become proficient in playing.

A further object of the invention is to provide a game apparatus of this kind which 20 is of simple construction and low manufacturing cost, and which may be readily taken down and packed for storage or shipment, and which presents a neat and attractive appearance when on display.

25 In the accompanying drawings I have illustrated my improved game apparatus as having for a target a group of pockets of different scoring values into which the projectile is projected during the playing of 30 the game.

In said drawings

Fig. 1 is a plan view of my improved game apparatus;

35 Fig. 2 is a sectional view on line 2—2 of Fig. 1;

Fig. 3 is a perspective view of the projecting apparatus detached from the board;

Fig. 4 is a similar view of a modified form 40 of the projecting apparatus; and

Fig. 5 is an enlarged detail view showing the means for connecting the projecting apparatus to the board.

Referring to the drawings, 1 indicates the 45 game board, which may be of any desired shape and dimensions, and is here shown as a long, narrow board having at one end a series of pockets or depressions 2 arranged in triangular form in the manner in which ten-pins are usually set up on an alley. The 50 board is provided with a rim 3 for confining the projectile to the surface of the board. The projecting apparatus comprises a chute 4 formed of two rods or heavy wires 5 maintained in spaced relation by small cross-wires 6 spot-welded or otherwise secured to 55 the under surface of the large wires. The

chute or runway 4 preferably extends the full length of the board and is attached to the board at the end remote from the pockets 2. At the end which is attached to the board, two wires 5 are spread apart as shown at 7 to provide an opening large enough for the marble or ball to drop through. The two wires 5 are bent backward under the opening 7 to provide a short 60 chute or runway and extending in the opposite direction from the main runway, to thereby direct the ball back toward the pockets 2, or other target.

The wires are given a reverse bend at the 65 end of the short runway 8 and spread out to form a base 9, and beyond the base are bent to form an eye 10 by means of which the runway is fastened to the base of the board.

1. In making up the runway a single wire 70 may be used, the loop forming the eye 10 being formed in the middle of the length of the wire and the ends then bent, as shown, to provide a runway having the features just described. The runway preferably extends 75 beyond the far end of the board, and for convenience in packing is made of two sections fastened together with a metal clip which may be welded or otherwise secured 80 to the end of one of the sections.

85 The eye 10 is fastened to the board by means of the bolt 11 over which the eye fits loosely. The head of the bolt is spaced somewhat from the face of the board and the compression spring 12 is arranged between the head of the bolt and the eye 10 to normally hold the eye flat against the board 90 while permitting it to be tilted and turned about the bolt for the purpose of directing the ball and varying its speed. By turning 95 the runway about the bolt in the plane of the surface of the board the projectile may be aimed at any one of the pockets or other targets with which the game is provided. By 100 tilting the runway to thereby vary the angle of inclination of the portion 8 of the runway, the speed of the ball may likewise be controlled. Thus, by raising the outer end of the runway 4 where it is normally held by 105 the player, the steepness of the portion 8 of the runway will be lessened and the speed of the projectile correspondingly reduced. Conversely, if the outer end of the part 4 is depressed, the portion 8 will be tilted toward 110 the vertical and its steepness correspondingly increased. In this way the player can exercise some skill in aiming the ball and

determining its velocity. In games of this kind, where a fixed runway for the ball is used, the result of the play is altogether a matter of chance, but with the game apparatus of this application a sufficient element of skill is introduced for the player to select a particular pocket or other objective and direct his efforts toward putting the ball in that particular pocket, thereby greatly enhancing the interest in the game.

In Fig. 4 there is illustrated a modified form of runway wherein the part 4 of the runway is made of two sheet metal parts telescoping one within the other after the manner of a curtain rod. This construction is of low manufacturing cost, and also permits the total length of the runway to be varied, as desired.

I claim:

1. In an apparatus of the class described, the combination of an objective at one end of the game board, a runway extending across the game board and attached to the end opposite the objective, said runway being constructed to reverse the direction of the projectile rolling down the runway, said fastening comprising a swivel joint permitting the angular adjustment of the runway in the plane of the board, substantially as described.

2. In an apparatus of the class described, the combination of an objective at one end of the game board, a runway extending across the game board and attached to the end opposite the objective, said runway being constructed to reverse the direction of the projectile rolling down the runway, said fastening comprising a swivel joint permitting the angular adjustment of the runway in a plane at right angles to the board, substantially as described.

3. In an apparatus of the class described, the combination of an objective at one end of the game board, a runway extending across the game board and attached to the end opposite the objective, said runway being constructed to reverse the direction of the projectile rolling down the runway, said fastening comprising a swivel joint permitting the angular adjustment of the runway in both the vertical and the horizontal plane.

4. In an apparatus of the class described, the combination of an objective at one end of the game board, a runway extending across the game board and attached to the end opposite the objective, said runway being constructed to reverse the direction of the projectile rolling down the runway, said runway comprising a pair of spaced rods or wires bent at their lower ends to provide a reversely-directed portion with an overlying opening for the passage of the ball from one portion to the other, substantially as described.

5. In an apparatus of the class described, the combination of an objective at one end of the game board, a runway extending across the game board and attached to the end opposite the objective, said runway being constructed to reverse the direction of the projectile rolling down the runway, said runway comprising a pair of spaced rods or wires bent at their lower ends to provide a reversely-directed portion with an overlying opening for the passage of the ball from one portion to the other, and a base portion extending back of said reversely-directed portion and having a loose swivel connection with said board, substantially as described.

In testimony whereof I affix my signature.

CHARLES DIETRICH.
